Inventor:
John Jacob Kaufmann,
By Jas. C. Nobusmith
Attorney

UNITED STATES PATENT OFFICE.

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed August 27, 1927. Serial No. 215,805.

My invention relates to heddle frames for looms, and it relates more particularly to improved means, in a heddle frame of the usual type, for supporting the heddle bars intermediate their ends.

The principal object of my present invention is to provide improved means in a heddle frame for supporting the heddle bars intermediate their ends, which will securely support said bars against undesirable motion and displacement, but which, however, will permit the bars to be quickly and conveniently mounted in and dismounted from the frame when desired.

In U. S. Patent No. 1,512,935, dated October 28, 1924, there is shown a device for supporting the heddle bars intermediate their ends which permits the bars to be easily and conveniently inserted in and removed from the heddle frame.

My present invention contemplates certain improvements in the device shown and described in the Letters Patent above mentioned, whereby the supporting device may be adjusted with respect to the top and bottom rails of the frame, so that the heddle supporting bars will be properly positioned and the heddles will not bind on the supporting bars, or on the other hand be permitted too great an up and down movement thereon.

The nature and characteristic features of my present invention will be more readily understood from the following description, taken in connection with the accompanying drawings forming part hereof, in which:

Figure 1 is an elevational view of a heddle frame provided with a heddle bar supporting device embodying the main features of my present invention;

Fig. 2 is a fragmentary detail thereof, enlarged;

Fig. 3 is a sectional view taken approximately on the line 3-3 of Fig. 2, the parts being shown in the normal positions assumed while supporting the heddle bar;

Fig. 4 is a similar view, but with the parts in the open position for the purpose of removing or mounting the heddle bar therein;

Fig. 5 is a perspective view of a bolt member constituting one of the principal novel elements of the present invention; and

Fig. 6 is a similar perspective view of a slidable locking member, detached, constitut-

ing another of the novel elements of the device.

Referring to the drawings, the heddle frame there shown comprises top and bottom rails 10, connected at their ends by means of the side strips 11. Extending from end to end of the heddle frame and arranged near the top and bottom rails 10, in the usual manner, are the heddle supporting bars 12, on which heddles 13 are mounted in the customary manner.

The devices comprising the novel portion of the present invention are mounted at suitable locations on the inner edges of the top and bottom rails 10. Each of these devices includes a bolt member 20, having a shank 21, the end of which is threaded as at 22 in the manner similar to an ordinary wood screw, with the exception that the same is not tapered for the greater portion of its length.

The bolt member 20 is also provided with a head portion 23, preferably made by flattening and spreading the material of the rod from which the bolt member is formed. The head portion of the bolt member is also provided with a recess 24, in which the heddle bar 12 is adapted to be seated.

Mounted on the head portion of the bolt member 20 is a slide member 30. The slide member 30 is provided with a longitudinal slot 31, and an opening 32 extends from the slot 31 to the marginal edge of the slide member 30. The opening 31 is located approximately midway the extension of the slot 31.

One end of the slide member 30 is bent over as at 33, and the bent over portion 33 is provided with an aperture 34, through which the shank portion of the bolt 20 extends. In this manner one end of the slide member 30 is properly positioned with respect to the head portion 23 of the bolt 20.

The other end of the slide member 30 is positioned with respect to the head portion of the bolt member 20 by means of a rivet 36 which extends through a portion of the slot 31 of the slide member 30, beyond the opening 32. The rivet 36 is secured in the end of the head portion 23 of the bolt member 20 beyond the recess 24 thereof.

The portion of the slide member 30 adjacent the bent over portion 33 thereof is bent out of the main plane of the slide member, as at 35, to clear the shank portion of the bolt

20 and also to afford a larger seat upon the bent over portion 33 of the slide member.

A coil spring 40 surrounds the smooth or unthreaded portion of the shank 21 of the bolt 20. Said coil spring 40 bears at one end against the bent over portion 33 of the slide member 30, and at its other end against the surface of the inner edge of the rail 10 of the heddle frame proper. If desired, a washer 41 5 may be interposed between the end of the coil spring 40 and the bent over portion 33 of the slide member 30.

The spring 40 normally tends to cause the slide member 30 to occupy a position as shown 15 in Fig. 3 of the drawings, whereby the lip 37, which extends from one end of the slot 31 to the opening 32 of the slide member, will lap over and retain the heddle bar 12 within the recess 24 of the head portion 23 of the 20 bolt 20.

The movement of the slide member under the tension of the spring 41 is limited by the bent over portion 33 of the slide member bearing against the shoulder provided where the 25 flattened head 23 joins the shank portion 21 of the bolt member.

The operation of the device may now be readily understood. The supporting devices being mounted in the heddle frames at desired 30 locations upon the inner edges of the top and bottom rails 10 thereof, and the heddle bars with the heddles mounted thereon being placed in the frame in the usual manner, with the ends thereof secured in position in 35 the side strips 11 of the frame by fastening devices of any preferred type, the slide member 30 is then manually pushed to the open position as shown in Fig. 4 of the drawings.

The heddle bar 12 is now inserted in the 40 recess 24 provided in the head portion 23 of the bolt 20, and thereafter the slide member 30 is released and permitted to return to the normal locking position as shown in Fig. 3 of the drawings, being thereafter held by the 45 coil spring 40.

The lip portion 37 of the slide member 30 will now serve to retain the heddle bar 12 within the recess 24 of the head portion 23 of the bolt 20, and will securely hold the same 50 against displacement during the operation of the loom.

When it is desired to remove the heddle supporting bar from the supporting device, it will be necessary merely to again push and 55 hold the slide member 30 in the position shown in Fig. 4 of the drawings, and the heddle bar 12 may then be readily disengaged from the supporting device.

Should it be found at any time that the 60 heddle supporting bars 12 are so located that an undue tension is placed upon the heddles whereby the same will bind upon the heddle supporting bars, or on the other hand, should it be found that the heddle bars are so positioned that the heddles are permitted too

much up and down movement in the frame, the proper adjustment of the device for supporting the heddle bars may be easily made by first removing the heddle bar from the supporting device, and then threading the 70 bolt in or out with respect to the rail 10 in which it is mounted until the recess 24 of the head portion 23 of the bolt 20 is properly located.

It will be seen that with devices constructed 75 as hereinbefore described, the heddle bars will be efficiently supported intermediate their ends whereby undue lateral movement of the same will be effectively prevented, and that adjustment of the supporting device with respect to the top and bottom rails may be quickly and conveniently made, so that the heddle bars may at all times be properly positioned.

Having thus described the nature and characteristic features of my invention, what I 80 claim as new, and desire to secure by Letters Patent, is:

1. In a heddle frame, the means for supporting the heddle bars intermediate their ends, comprising a bolt member threaded 90 directly in the heddle frame rail, said bolt member having a flattened head portion provided with a recess adapted to receive and support the heddle bar, and a member slidably mounted on said bolt having a central 95 slot and an opening extending from said slot to the side margin of said slidable member, said slot and opening forming an overlapping lip adapted to engage the heddle bar and lock the same in the recess in the head of the bolt, one end of the slidable member being bent over and being provided with an aperture in said bent over portion through which the shank of the bolt passes.

2. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted on said bolt having a central slot and an opening extending from said slot to the side margin of said slidable member, said slot and opening forming an overlapping lip adapted 115 to engage the heddle bar and lock the same in the recess in the head of the bolt, the upper end of the slidable member being bent over and being provided with an aperture in said bent over portion through which the shank of the bolt passes, and a rivet passing through the slot in the slidable member and secured to the head portion of the bolt.

3. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted 130

- on said bolt having a central slot and an opening extending from said slot to the side margin of said slidable member, said slot and opening forming an overlapping lip adapted to engage the heddle bar and lock the same in the recess in the head of the bolt, one end of the slidable member being bent over and being provided with an aperture in said bent over portion through which the shank of the bolt passes, and resilient means adapted to impel said slidable member to the locking position.
4. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted on said bolt having a central slot and an opening extending from said slot to the side margin of said slidable member, said slot and opening forming an overlapping lip adapted to engage the heddle bar and lock the same in the recess in the head of the bolt, one end of the slidable member being bent over and being provided with an aperture in said bent over portion through which the shank of the bolt passes, and a coil spring mounted on the shank of the bolt adapted to impel said slidable member to the locking position.
5. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted on said bolt having a central slot and an opening extending from said slot to the side margin of said slidable member, said slot and opening forming an overlapping lip adapted to engage the heddle bar and lock the same in the recess in the head of the bolt, one end of the slidable member being bent over and being provided with an aperture in said bent over portion through which the shank of the bolt passes, and a coil spring mounted on the shank of the bolt adapted to impel said slidable member to the locking position.
6. In a heddle frame, the means for supporting the heddle bars intermediate their ends, comprising a bolt member threaded directly in the heddle frame rail, said bolt member having a flattened head portion provided with a recess adapted to receive and support the heddle bar, a member slidably mounted on said bolt having a central slot and an opening extending from said slot to the side margin of said slidable member, said slot and opening forming an overlapping lip adapted to engage the heddle bar and lock the same in the recess in the head of the bolt, one end of the slidable member being bent over and being provided with an aperture in said bent over portion through which the shank of the bolt passes, a rivet passing through the slot in the slidable member and secured to the head portion of the bolt, and a coil spring mounted on the shank of the bolt adapted to impel said slidable member to the locking position.

In testimony whereof, I have hereunto signed my name.

JOHN JACOB KAUFMANN.
